CLAIM

The ornamental design for a jewelry chain, as shown and described.

DESCRIPTION

FIG. 1 is a top plan view of a sectional length of a jewelry chain according to the invention, shown in a non-fastened, non-use position, the bottom plan view being a mirror image;

FIG. 2 is a side edge elevation view thereof from one side, the opposite side edge view being a mirror image;

FIG. 3 is an end edge elevation view thereof, the view from the opposite end being a mirror image; and,

FIG. 4 is an elevation view of a sectional length of the jewelry chain shown in a fastened, use configuration thereof applied as an armband.
